ABSTRACT: In such a filter, as the drum rotates, a layer or sheet of pulp material collected from the bath upon the filter media of the drum, emerges at the ascending side of the drum. Feed suspension or pulp is supplied continuously to the vat, so that the sheet may be delivered continuously at the descending side of the filter drum, while separated filtrate liquid passes continuously from the drum. A cake-washing phase and subsequent cake-drying phase may be interposed between the points of cake emergence and cake discharge, at the top side of the filter drum.

ROTARY DRUM FILTER

This application is a continuation of Ser. No. 611,077, filed Jan. 23, 1967, and now abandoned.

More particularly, the invention relates to rotary drum filters of the type that may be employed advantageously for the dewatering and washing or rewashing of fibrous pulps, for example bleach pulp from the bleach towers, or the like. In such pulp treatment or washing operations great volumes of liquid or liquor must be handled by such filters also called pulp washers or thickeners which may be required to form sheets or layers of material on the filter media of the drum, having a moisture corresponding to a solids concentration of, say, 12 percent to 14 percent from a dilute feed pulp of perhaps only 0.35 percent to 1.0 percent.

In conventional pulp filters a solid cylindrical drum member is mounted for rotation by means of trunnions upon the end walls of the vat. One trunnion is connected to a drive for rotating this drum member. Upon the outside of the drum member there are provided filtrate drainage channels substantially parallel to the drum axis and adjoining one another.

Filter media itself are placed over these drainage channels around the drum. The drainage channels thus covered or closed by the filter media are open at one end of the drum for filtrate discharge. This filtrate discharge end of the drum and the discharge ends of the drainage channels are sealed against the pulp in the vat and where necessary also sealed against the atmosphere, allowing the filtrate liquid to discharge into the atmosphere, or into the vacuum of a barometric leg. Some types of filters therefore employ the so-called deckle strap devices which have a stationary deckle strap element in sealing contact with the periphery of the drum. In other types, a stationary vacuum box is placed sealingly against the very end of the drum, in order that the ends of the drainage channels of the drum may communicate with the vacuum of a barometric leg, aided by the static head of the feed pulp in the vat. The filtration cycle may comprise sheet-forming, and sheet-washing zones, as well as a zone for the continuous discharge of the finished sheet or filter cake.

A problem encountered in such filters is that of maintaining desired optimum vacuum effects while minimizing the required length of the barometric leg. Saving height of the barometric leg means lower building construction cost, as well as lower filtrate pumping cost as in countercurrent bleach-washing operation where several wash filters operate in series, each on its own barometric leg. Thus, spent wash liquor from one filter must be pumped back to height of the preceding filter.

Heretofore, a structural difficulty lay in the fact that in those filters the filtrate discharge outlet could not be located low enough relative to the lowest or 6 o'clock position of the drainage channels on the drum. If the location of the filtrate outlet is located higher than the 6 o'clock position, the resulting negative head in the vat will not only reduce the available positive static head of the feed pulp in the vat, but will also detract from the filtration and filtrate drainage capacity of the drum.

Another problem is that of providing simple and effective sealing means between the stationary parts and the filter drum, to seal against the feed pulp in the vat, as well as against the atmosphere. These sealing means should seal evenly and wear evenly along the periphery of the filter drum, and should be readily accessible and serviceable. Frictional power loss incurred in the operation of these sealing means should be minimized. Particularly objectionable is the brake band effect of the conventional deckle strap devices.

Other frictional loss is incurred due to the operation of the so-called "bridges" in the vacuum box, that is, the partitioning which functionally separates sequential operating zones of the filter-operating cycle from one another to avoid short circuiting between the zones. Heretofore, this sealing effect had to rely upon sliding contact or close-tolerance fitting between the "bridges" and the rotating drum.

Another problem is that of mounting and supporting the vacuum box in cooperative relationship with the filter drum.

Heretofore, the atmospheric pressure exerted upon that box would tend to press the same against the associated end of the filter drum. Moreover, heretofore because of the endwise location of the vacuum box, the design and support of the associated end trunnion of the filter drum and its accessibility have also presented difficulties.

It is among the objects of this invention to overcome the foregoing problems and shortcomings in the construction and operation of the filters, and to provide an improved filter unit of generally simplified economical construction. More particularly, the filter unit should require little if any close-tolerance work between the vat structure, the vacuum box, and the filter drum, and it should be capable of being readily assembled. Furthermore, this filter unit should have optimum sheet-forming capacity, provide a vacuum with optimum gravity assist from the feed pulp in the vat, should have optimum internal hydraulic and drainage characteristics, and should have deckle strap sealing means of great simplicity that will seal and wear uniformly, are readily accessible, adjustable and replaceable, and are self-compensating for wear and tear. Furthermore, the filter unit should be economically operable with relatively low power consumption by minimizing the aforementioned friction losses and by the use of a relatively short barometric leg.

The foregoing objects are attainable mainly by incorporating the vacuum box into the vat structure itself, in such a manner that the filtrate and wash liquors will flow from the drainage channels of the filter drum directly downwardly into the barometric leg. According to the invention, the vacuum box is in the form of an annular structure herein also termed the peripheral valve or perimeter valve surrounding the drum in direct communication with the drainage channels of the drum. Positive static head of feed pulp in the vat as well as the sheet-forming potential of all the drainage channels on the drum may thus be fully utilized. Simplified and more effective sealing means are provided in the form of a pair of improved self-compensating deckle strap devices associated with respective sides of the annular channel structure, featuring an endless deckle strap element which rotates with the drum, and has lateral sealing contact with the stationary channel structure. Liquid traps or water pockets are provided instead of close tolerance or frictional sealing means or bridges that functionally separate respective phases or zones of the filtration cycle.

More particularly, the vacuum box or stationary annular valve structure surrounds the filter drum with substantial clearance, traversing the longitudinal ribs which constitute the drainage channels on the drum. This annular valve structure is partitioned or functionally divided into arcuate sections defining the sequential zones or phases of the filter-operating cycle.

The filtrate liquid passing through the filter media flows along the longitudinal horizontal drainage channels into an annular collecting space or peripheral open zone or channel on the filter drum, that is a zone not covered by the filter media, but surrounded by the aforementioned peripheral valve structure, and which delivers filtrate liquid directly downwardly into and through a barometric leg. A deckle strap device is provided at each side of the annular channel structure for maintaining the operating vacuum by sealing that structure with respect to the rotating drum.

The peripheral valve structure is horizontally split into a lower arcuate portion structurally integrated into the vat, and a complementary upper arcuate portion or archlike member detachably but rigidly and tightly secured to the lower arcuate portion. Thus, when assembling the filter unit, one need only place the filter drum into its trunnion bearings on the end walls of the vat so as to have the lower part of the annular collecting channel of the filter drum register with the arcuate channel portion of the vat, then place the separate complementary arcuate valve member over the filter drum to cover and register with the remaining part of the collecting channel of the filter drum, and then rigidly and tightly securing that member to the vat. The two deckle strap devices may then be

readily applied by threading them into place around the drum at the respective sides of the annular valve structure, for sealing the vacuum system against the feed pulp in the vat, as well as against the atmosphere. The required operating vacuum is thus maintainable in respective operating zones of the filtration cycle as defined by the compartmentation provided in the annular valve structure. Nonfrictional hydraulic seals are provided within the annular valve structure for functionally separating or "bridging" the operating zones from one another.

Specific features are found in the construction and internal compartmentation of the annular valve structure, defining the filter-operating cycle, and also in the arrangement of nonfrictional water seals in the annular channel structure, functionally separating the zones or phases of the filtration cycle.

Still other features are found in various structural and functional aspects of the deckle strap devices, involving low-friction characteristics and the ability to automatically and evenly compensate for wear and tear.

The peripheral or perimeter valve construction of this invention may be disposed midway between the ends of the drum, so that the filtrate liquid in the drainage channel may reach the annular collecting zone rapidly from both ends of a long filter drum before discharging in stream-flow fashion directly downward through the surrounding channel structure into the barometric leg.

Other features and advantages will hereinafter appear.

FIG. 1 is a longitudinal vertical sectional view of one embodiment of the filter unit, showing the peripheral valve structure surrounding the filter drum midway between the ends of the filter unit, and sealed by a pair of deckle strap devices, with the drum shaft sealingly penetrating the end walls of the vat.

FIG. 1a is a detail sectional view taken on line 1a-1a in FIG. 1.

FIG. 2 is a vertical transverse sectional view of the filter unit taken on line 2-2 in FIG. 1, showing the partitioning or "bridging" within the filter box, which define the operating zones of the filtration cycle.

FIGS. 2a through FIG. 2h are detail sections of the peripheral valve structure taken respectively on lines 2a-2a through 2h-2h.

FIG. 3 is a greatly enlarged detail view taken from FIG. 1, showing a cross section of the top part of the peripheral valve structure and of the deckle strap devices.

FIG. 3a is a further enlarged detail cross-sectional view of one of the deckle strap devices of FIG. 3, illustrating the feature of uniform wear and tear.

FIG. 3b is an enlarged fragmentary longitudinal sectional view of one form of the deckle strap.

FIG. 3c is a detail cross-sectional view of another form of the deckle strap device.

FIG. 3d is a sectional view taken on line 3d-3d in FIG. 3c.

FIG. 4 is a longitudinal vertical sectional view of another embodiment of the filter unit showing the vacuum box surrounding one end of the filter unit.

FIG. 5 is a vertical transverse sectional view taken on line 5-5 in FIG. 4, showing one end of the filter drum peripherally sealed by one of the deckle strap devices.

FIG. 6 is a greatly enlarged detail view taken from FIG. 4, showing the vacuum box with the deckle strap devices.

FIG. 7 is a transverse sectional view of the vat structure of FIG. 1 separated from the filter drum, showing the lower part of the peripheral valve integrated in the vat, and the upper complementary part in the form of a detachable arch member connected to the vat.

FIG. 8 is a sectional view taken on line 8-8 in FIG. 7, looking downward upon the vacuum box portion of the vat structure.

FIG. 9 is a sectional view taken on line 9-9 in FIG. 7, looking upward upon the bottom side of the arch member of the vacuum box.

FIG. 10 is an outside view upon the cake discharge side of the filter unit of FIG. 1.

FIG. 11 is an end view taken on line 11-11 of the filter unit of FIG. 10.

FIG. 12 is a side view, at reduced scale, of the filter drum per se, taken from the filter unit of FIG. 10, with some of the filter media removed.

FIG. 13 is a cross-sectional view taken on line 13-13 of the filter drum of FIG. 12.

FIG. 14 is an outside view upon the cake discharge side of the filter unit of FIG. 4.

10 FIG. 15 is an end view taken on line 15-15 of FIG. 14.

FIG. 16 is a side view, at reduced scale, of the filter drum per se taken from the filter unit of FIG. 14, with the filter media omitted.

FIG. 17 is a cross-sectional view taken on line 17-17 of the filter drum of FIG. 16.

FIG. 18 is a reduced semidiagrammatic cross-sectional view of a filter unit similar to FIG. 2 complete with gravity and barometric discharge legs.

20 FIG. 19 is a longitudinal vertical sectional view of a modified form of the drum filter shown in FIG. 1, featuring a recessed annular filtrate-collecting channel midway between the ends of the filter drum.

25 FIG. 20 is a cross-sectional view on line 20-20 in FIG. 19, showing the zones of a filtration cycle in connection with the peripheral valve structure, along with respective filtrate discharge legs.

FIG. 20a is a detail sectional view taken on line 20a-20a in FIG. 20.

30 FIG. 21 shows the peripheral valve structure of FIG. 20, separate from the filter drum.

FIG. 22 is a horizontal sectional view on line 22-22 in FIG. 21, looking downward upon the valve portion of the vat.

35 FIG. 23 is a horizontal sectional view on line 23-23 in FIG. 21 looking upward upon the complementary arcuate valve member.

FIG. 24 is a longitudinal vertical sectional view of a modified form of the drum filter shown in FIG. 4, featuring a recessed annular filtrate-collecting zone at the end of the filter drum.

40 FIG. 25 is a vertical transverse sectional view on line 25-25 in FIG. 24, showing a deckle strap anchored laterally upon the peripheral valve construction.

FIG. 25a is an enlarged detail view taken from FIG. 25, showing the anchoring of both ends of the deckle strap.

FIG. 25b is a further enlarged and further detailed end view of the anchoring of one end of the deckle strap, taken on line 25b-25 in FIG. 25a.

FIG. 25c is a sectional view of the anchoring of FIG. 25b, taken on line 25c-25c in FIG. 25b.

FIG. 25d is an enlarged detail view of the cross section of the peripheral valve, taken from FIG. 24, including the cross section of a novel tubular deckle strap anchored as in FIG. 25a.

55 FIG. 25e is the cross section of another kind of tubular deckle strap which may be anchored as in FIG. 25a.

FIG. 25f is the cross section of still another deckle strap having circular cross-sectional configuration, which may be anchored as in FIG. 25a.

60 FIG. 26 is an enlarged detail view taken from FIG. 19, of the deckle strap devices at each side of the peripheral valve construction.

FIG. 27 is an enlarged detail view taken from FIG. 24, of the deckle strap devices at each side of the peripheral valve construction.

65 FIG. 28 is a side view upon the cake discharge side of the drum filter of FIG. 19, with parts of the vat wall broken away to show the recessed annular filtrate-collecting channel.

FIG. 29 is an end view on line 29-29 of the drum filter of

70 FIG. 28.

FIG. 30 is a side view upon the cake discharge side of the drum filter of FIG. 24, with parts of the vat wall broken away to show the recessed annular filtrate-collecting channel.

FIG. 31 is an end view on line 31-31 of the drum filter of

75 FIG. 30.

Since the invention features the provision of the peripheral valve construction herein also termed peripheral vacuum box, providing direct communication with the longitudinal drainage channels of the filter drum, that feature may be embodied in the filter unit of FIG. 1 having the vacuum box disposed midway between the ends of a relatively long filter drum, or in the filter drum of FIG. 4 where the vacuum box surrounds the end of a relatively shorter drum. With that common feature, both embodiments provide the basic advantages of direct downward stream flow path of filtrate drainage from the filter unit into the barometric leg, as well as other structural and operational gains such as will hereinafter appear.

Referring to the one embodiment of FIG. 1 and the related FIGS. 2, 3, 3a, 3b, and 7 to 13, the filter unit comprises a filter drum 10 mounted for rotation on a vat structure 11 to which the pulp to be filtered is continuously fed at 11a. The filter drum has end trunnions 12 and 13 supported in respective bearings 14 and 15 which in turn are mounted upon the end walls 16 and 17 of the vat structure. The walls of the vat extend upwardly beyond the trunnions, in order to provide for deep immersion operation, that is immersion of the drum into the pulp bath to a depth substantially beyond the trunnions or beyond the horizontal axis of the drum. Therefore, the trunnions must penetrate the end walls of the vat, and respective stuffing boxes 18 and 19 must be provided for them to seal off that penetration.

From FIGS. 1 and 1a it will be seen that each trunnion penetrates a shield plate 19a which together with the stuffing box is detachable from the respective end wall of the vat, a watertight connection between the shield plate and the end wall being indicated at 19c.

The filter drum comprises a solid cylinder 20 herein called the drum cylinder closed by end plates 21 and 22 to which trunnions 12 and 13 are fixed. The trunnion members penetrate the end plates, and have an inner end portion 23 from which extend spider arms 24 reinforcing the plates. An internal hub plate 25 reinforces this spider construction. Internal annular ribs 25a provide reinforcement for the cylinder 20.

Externally upon each end portion of the drum there is provided a set of longitudinal ribs or division strips 26 equally spaced about the periphery of the drum, and constituting filtrate flow channels 27. At their inner ends the two sets of ribs terminate a distance D from each other, thus defining between them an annular filtrate collecting channel 28 upon the drum cylinder 20.

Surrounding each set of division strips or drainage channels are filter media 28a having backing support in the form of the customary wire 29 wound spirally around each set of ribs, the winding pitch of the wire being determined by notches in the ribs, which accommodate the wire. The outer end of each set of drainage channels is closed by an annular rim 30 which has a peripheral ledge 31 for supporting and fastening thereon the adjacent outer edge portion of the respective filter media. Surrounding the inner ends of each set of ribs and fastened thereto, as by welding, is an annular band 32 providing a base for fastening the adjacent inner edge portion of the respective filter media.

The annular collecting channel 28 on the rotary filter drum is surrounded by a stationary annular channel structure 33 herein also termed the annular vacuum box receiving filtrate and wash liquid from channel 28 for discharge directly downwardly from the filter unit, that is through the bottom of the vat partially through a gravity discharge leg 34 into the atmosphere, and partially through a barometric leg 35, such discharges being effected in a manner and under conditions that will be furthermore described. The lower part of the annular vacuum box indicated by the height H-1 is integral with or part of the vat, while the upper part of this annular box indicated by the height H-2 is in the form of a detachable arch member rigidly flange connected to the lower part at K. A pair of special deckle strap devices 36 and 37 are provided one at each side of channel structure 33 for maintaining therein a

required operating vacuum by sealing that structure against the rotating drum, and to be described in more detail below.

The stationary annular vacuum box is horizontally split in a plane P located a distance H-3 above the axis of rotation of the filter drum. Therefore, this vacuum box (see FIGS. 2 and 7 to 9) comprises a major lower portion 39 unitary with or integrated in the vat structure, and a complementary portion in the form of an arch member 40 having flange connection K with the lower channel portion. The lower channel portion has a first flanged rectangular outlet opening or short neck 42 for connection with the gravity discharge leg 34, and a second rectangular flanged outlet opening or short neck 44 for connection with the barometric discharge leg 35. With the drum rotating in counterclockwise direction as indicated by arrows A in FIGS. 2, 11, 18, the gravity leg discharge is associated with, and serves a gravity filtration zone Z-1 at the lower descending portion of the drum, while the barometric leg discharge is associated with, and serves a vacuum filtration zone Z-2 at the lower ascending portion of the drum, all within a filtration cycle to be furthermore described, and relative to a pulp level which may be located about at P-L.

The annular vacuum box as a whole comprises a peripheral wall 45 having a rib 45a (see FIGS. 2 and 8) connecting it with the vat.

The sides 46 and 47 of the annular vacuum box each have an inner circular reinforcing rim portion 46b and 47b respectively. These rim portions have prepared outer lateral faces F-1 and F-2 parallel to one another and extending in planes at right angles to the axis of rotation of the drum. These rim portions have substantial clearances C-1 and C-2 relative to the rotary drum which clearances are sealed by novel ring-shaped deckle strap elements 46a and 47a respectively, rotating with the filter drum. These deckle strap elements are in the form of what might be called very large O-rings sealingly engaging the respective transverse faces F-1 and F-2 as well as respective prepared conical faces F-3 and F-4 provided on the respective annular terminal bands 32.

The deckle strap according to the invention comprises a length of resiliently flexible tubing 48a as of rubber or the like, containing what in effect is an endless coil spring holding the tubular ring formation with the ends thereof buttwise adjoining one another. Thus the deckle strap is tensioned around the respective associated conical face sufficiently to rotate together with the drum, the conical face together with the atmospheric pressure maintaining the ring element in sealing contact with the associated lateral face of the vacuum box. This novel deckle strap arrangement avoids the brake band effect and frictional power loss of conventional stationary flat deckle straps. At the same time, this ring-shaped deckle strap will be subject only to relatively slow or moderate wear uniformly distributed along its entire length as illustrated in FIG. 3a, the degree of such wear being readily observable. The internal endless spring in fact consists of a large number of short coil springs 48 hooked endwise to one another, so that the internal contractile tension of the ring member can be varied for instance by the removal or insertion of a component spring.

Because of the tubular formation of the deckle strap elements, these elements will automatically, by rolling upon the conical supporting surface, adjust themselves to any degree of thermal longitudinal expansion of the filter drum relative to vat structure and the vacuum box.

The annular vacuum box 33 is provided internally with stationary partitions or bridge structures herein simply termed "bridges" B-1, B-2, B-3, B-4, spaced from one another along the periphery of the vacuum box, providing blank-off zones Z-6, Z-7, Z-8, Z-9. Functionally these bridges define between them the various operating phases or zones Z-1 through Z-5 of the filter-operating cycle. These bridges subdivide the vacuum box by extending into the annular collecting channel 28 on the drum cylinder, with bridge plates substantially conforming to the cross-sectional area of the collecting channel. These bridges are herein preferably designed to

avoid close tolerance requirements or rubbing contact between the stationary and the rotating parts, by way of providing liquid-sealing means or liquid-collecting pockets for the bridges, such as will be furthermore described.

Accordingly, the bridge B-1 comprises a radial baffle wall 49 substantially conforming to the cross-sectional contour of the collecting channel 28 on the drum, and having a lateral shelf 49a directed towards the gravity filtrate outlet 42 and together with wall 49 constituting a pocket P-1 adapted to provide a liquid seal.

The bridge B-2 comprises a substantially vertical although slightly curved partition or baffle wall 50 spaced from the peripheral wall of the vacuum box and extending substantially parallel thereto and providing therewith an outer drainage channel 51. The bridge itself is in the form of a shelf 52 extending from the baffle wall into the collecting channel 28 on the drum, and together with the baffle wall 50 and with the drum cylinder constituting a pocket P-2 adapted to provide a liquid seal.

The bridge B-3 comprises a radial baffle wall 53 having a shelf 54 and lateral baffle walls 55 and 56 (see detail FIG. 2e) which latter together with the wall 53 and shelf 54 constitute a pocket P-3 adapted to provide a liquid seal. The lateral walls 55 and 56 of this pocket are dimensioned to blank off at least a single filtrate flow channel of the drum, so as to prevent short circuiting due to pressure differential between the respective adjoining operating zones Z-3 and Z-4, which zones in turn communicate respectively with the barometric discharge leg 35 and with the gravity discharge leg 34.

The next bridge structure B-4 comprises a substantially vertically extending although curved partition or baffle wall 57 extending within the vacuum box substantially parallel to the peripheral wall thereof and spaced therefrom so as to constitute a downward flow channel 58. From the upper end of this curved baffle wall extends a shelf 59 providing the bridge plate proper extending into the collective channel 28 of the filter drum. This shelf in cross section appears as an angle profile having shanks 59a and 59b enclosing an obtuse upwardly open angle, and having sidewalls 59c and 59d (see detail FIG. 2f) constituting therewith a pocket P-4 adapted to provide a liquid seal. Again, the sidewalls of this pocket are so dimensioned as to blank off at least one of the drainage channels at a time, so as to avoid short circuiting between the adjoining operating zones Z-4 and Z-5.

Referring particularly to FIGS. 2 and 18, the filter operating cycle comprising the aforementioned operating zones Z-1 through Z-5 and the neutral or bridge zones Z-6 to Z-9, will now be described in more detail.

The zones Z-1 and Z-2 are sequential cake-forming zones operating at the lower submerged part of the drum, while the upper emerged part of the drum is subject to the effects of zones Z-3, Z-4 and Z-5 for filter cake washing, cake drying and cake discharge, respectively.

Furthermore, from the functional arrangement of the bridges in the vacuum box as herein shown and as above set forth, it will be seen that the operating zones Z-2 and Z-3 (collectively designated as zone Z-10) are subject to a vacuum effect of the barometric discharge leg 35 whereas the operating zones Z-1, Z-5 and Z-4 (collectively designated as zone Z-11) are subject to the effect of the atmospheric or gravity discharge leg 34.

In the operation of the filter cycle, the zone Z-1 at the cake discharge side of the drum, is subject to the static head of the feed pulp in the vat, causing a relatively loose initial or base layer of pulp fibers matted in an interlaced and relatively loose formation upon the filter media, while only static head forces initial filtrate liquid through the filter media into the respective filtrate channels of the drum, whence the liquid flows via the collecting channel 28 directly downwardly to gravity discharge leg 34. Although the filtrate discharge here is into the atmosphere, nevertheless the rapid and unobstructed direct downward flow (see flow arrows N and O) produces a relatively mild suction or vacuum effect aiding the initial cake

formation in this zone. In this way, the available static head thus made available by the invention is utilized to the greatest possible extent.

The next following zone in the direction of drum rotation, 5 and functionally separated from zone Z-1 by bridge B-1 is the vacuum filtration zone Z-2. Under the intensified suction influence of the barometric leg 35 added to the static head there is formed in this zone an additional, more substantial layer of 10 highly densified cake material, with the previously formed initial layer of matted material serving as a porous or drainage base capable of intercepting fines before they can reach and have a clogging effect upon the filter media or cloth. The sequential action of the two filtration zones results in relatively greater final cake thickness or filter capacity (in terms of 15 pounds of solids collected per unit of filter area), as well as in a longer uninterrupted operation of the filter unit.

The finished filter cake emerging on the ascending side of the drum then moves past the bridge B-2 through the zone 20 Z-3 where wash water from spray pipes 60 is delivered upon the filter cake for washing out residual pulp filtrate liquor. From this cake-washing zone the liquid discharges through the aforementioned vertical flow channel 51 communicating with the barometric leg. This downward flow channel or duct acts 25 as an auxiliary discharge leg providing additional suction effect upon the cake-washing zone. The flow from zones Z-2 and Z-3 is indicated by flow arrows N-2 and O-2 respectively.

With further drum rotation the washed filter cake moves past the bridge B-3 into the so-called cake-drying zone Z-4, 30 thus entering the aforementioned collective zone Z-11 which is under the influence of the gravity discharge leg 34 (see flow arrows N and O).

The aforementioned vertical curved channel or duct 58 provides discharge communication from the drying zone Z-4 to the gravity discharge leg. This channel itself also acts as an auxiliary discharge leg which adds to whatever suction is provided by the rushing of the filtrate liquid down through the gravity discharge leg.

Further drum rotation moves the filter cake past the bridge 40 B-4 into the zone Z-5 for cake discharge, which latter zone thus becomes a zone of vacuum release at the descending side of the drum. This vacuum release zone substantially extends from the bridge B-4 downwardly substantially to the point of 45 reimmersion where the filter media again enters the body of feed pulp in the vat.

From the foregoing description of the operating cycle it will be seen that the effectiveness of the barometric leg 35 as well as of the gravity discharge leg 34 is relatively enhanced, 50 because of the direct downward discharge in stream-flow fashion of the filtrate liquids made possible by the provision according to the invention of a vacuum box surrounding the filter drum. The hydraulic effectiveness of that arrangement is further aided by the supplemental suction effect of the auxiliary discharge legs 51 and 58 operating within this vacuum box. The filtrate liquids from the various operating zone thus pass through the filter and from the filter, without encountering delay or obstruction in the way of any negative static head.

A second embodiment of the filter unit of this invention as 60 illustrated in FIGS. 4, 5, 6, 14, 15, 16 and 17, provides the same main features and advantages and the same filtration cycle as described above. The difference therefore between the two embodiments lies merely in the fact that the annular vacuum box of the second embodiment surrounds one end portion of a shorter filter drum, instead of being disposed midway between the ends of a longer drum as above described.

Accordingly, in FIGS. 4 and 6 a vacuum box 62 similar to the one described above surrounds an annular collecting 70 channel 63 formed on the drum. This annular channel is formed between an annular end rim 64 provided at the extreme end of the drum cylinder 64a and spaced a distance d from the adjacent ends 65 of ribs or division strips 66 which constitute the filtrate channels 66a on the drum cylinder (see 75 FIGS. 16 and 17).

A terminal annular band 67 surrounding the end 65 of the strips 66 and welded thereto serves as a fastening base for filter media 68. Surrounding this annular terminal band 67 is an annular deckle strap element 69 which may be similar to the one above described. A similar deckle strap element 70 is provided at the opposite side of the vacuum box, surrounding and engaging a conical peripheral face 71 provided on the terminal rim 64. This latter deckle strap element may thus be fully exposed and accessible along its entire periphery although rotating together with the drum (see FIG. 5). Consequently, the vat at this end need have no end wall comparable to the end wall 72 required at the opposite end where the trunnion 73 is located below the pulp level in the vat. The opposite end of the drum cylinder is closed by end plate 64b reinforced by spider arm construction 64c extending from the trunnion 73.

The open end of the drum cylinder associated with the vacuum box may have its trunnion 74 rigidly connected to the drum cylinder as by means of a spider arm construction 75. This trunnion together with a drive mechanism 75a may be mounted in any suitable manner, for instance upon a beam construction 76.

According to FIGS. 3c and 3d another embodiment of the rotating ring-shaped deckle strap comprises a sealing strip 77 consisting of resiliently deflectable rubberlike material. A terminal annular band 78 is welded to the division strips, and is formed with an annular recess 79 or reduced end portion presenting a thrust shoulder 80 for the strip or deckle strap element 77 secured in place as by a flat wire or thin metal band 81 or the like.

A lap joint 82 connects the ends of this sealing strip which is initially flat but provides sealing contact with the adjacent side 82a of the vacuum box when resiliently deflected in the manner shown in FIGS. 3c and 3d.

In the embodiment of FIGS. 10 and 11 cake discharge rollers R-1 and R-2 separated by the intermediate similar suction box, are rotated from the drive mechanism M that rotates the filter drum. In the embodiment of FIGS. 14 and 15 a cake discharge roller R-4 and a gravity filtrate discharge leg 82b and barometric discharge leg 82c are shown.

A modified form of the filter unit of FIG. 1 is shown in FIGS. 19 to 23, 26, 28 and 29. This modified construction has a filter drum structure 85 which is formed midway between its ends with a recessed annular portion providing a recessed filter-collecting channel 86.

Thus, the drum structure comprises an intermediate short constricted cylindrical portion of diameter D-1 and length E-1, and cylindrical end portions of diameter D-2 and length E-2. Transverse annular wall portions 86a interconnect the intermediate cylindrical portion 86b with the wider cylindrical end portions 86c which latter carry drainage channels 87 formed by the ribs 88 surrounded by the usual spirally wound wire 89 supporting the filter media 90. The ends of the drum structure are closed by end plates 91 and 92 respectively, to which are fixed respective trunnion members 93 and 94. The ends of the drum structure are reinforced internally by radial members 95 of structural profile, the inner ends of which are fixed to the trunnion members. The intermediate portion of the drum structure is reinforced by radial members 96 of structural profile, connected rigidly to an axial tubular member 97. The filter drum is supported for rotation in bearings 98a and 98b mounted on respective end walls 99 and 100 of a vat V. The trunnion members penetrate the end walls of the vat in sealed relationship therewith so that the pulp level P.L. is maintainable in the vat a distance d-1 above the horizontal axis of the filter drum. Drive means for the filter drum are indicated at 101.

As indicated by arrows T-1 and T-2 in FIG. 19, the annular recess or collecting channel 86 of the drum structure allows filtrate liquid (see FIG. 19) to cascade directly from the inner ends of drainage channels 87 to the lower level of the annular recess or collecting channel and thus away from the filter media and from the cake formation thereon. This flow ar-

rangement further expedites the delivery of filtrate liquid from the drainage channels and from the filter drum into the discharge connections such as the barometric leg 88a and the gravity discharge leg 88b (see FIG. 20), while minimizing any chance of filtrate liquid rewetting the filter cake after its emergence from the pulp in the vat.

The peripheral valve construction in this embodiment (see FIGS. 19, 20, 21) surrounding the collecting channel 86, comprises the lower arcuate part 102 (indicated by the height L-1) integral with the vat V, and the complementary arcuate upper portion 103 (indicated by the height L-2) detachably fastened to the lower part 102 as indicated by the flange connections 104 comprising flanges 104a and 104b.

The upper arcuate part or member 103 of outwardly open U-shaped cross-sectional profile, comprises the arcuate bottom 105 and the sides or radial ribs 106 and 107. The arcuate bottom is in alignment with the outer periphery of the filter drum. The ribs will serve conveniently for the mounting of spray wash pipes 108, as well as for the support of cake discharge rollers or scrapers indicated at 109 in FIG. 28.

A pair of deckle strap devices S-1 and S-2 (see also FIG. 26) are provided for sealing each side of the peripheral valve construction against the rotating filter drum. The deckle strap element itself in each of these devices sealingly cooperates with the prepared conical face of an annular band 108a surrounding and fixed to the ribs 88, as well as with the adjacent prepared side face of the annular valve structure, and which extends transversely of the drum axis.

The lower part 102 of the peripheral valve construction is in the form of an inwardly open channel having sidewalls 102a and 102b, and an arcuate bottom portion 110 which is part of the vat itself, extending from point K-1 to point K-2. This bottom portion has upper terminal portions 111 and 112 which are inwardly inclined so that their end points K-3 and K-4 register with respective end points K-5 and K-6 of the arcuate upper complementary member 103.

The inclined terminal portion 111 constitutes together with the adjacent flange 104a a triangular pointed recess or niche N-1 in the side of the vat. The opposite side of the vat is formed with a recess R on either side of which there are the upper terminal vertical wall portions 116 of the vat. Feed pulp from feed trough 113 enters the tank at the full length L (see FIGS. 19 and 24).

The outline of the sidewalls 102a and 102b of the lower part 102 of the peripheral valve is defined by the arcuate line between end points K-3 and K-4 along the periphery of the filter drum, and by the arcuate line between points K-1 and K-2 along the profile curvature of the vat, and further by the line between points K-1 and K-4, and finally by the line between points K-2 and K-3.

The filtration cycle in this embodiment as indicated in FIG. 20 is generally the same as the one shown and described above in connection with the embodiment of FIG. 2. Accordingly, in FIG. 20 starting at the descending side of the filter drum and proceeding clockwise, there is a gravity sheet formation zone G-1, followed by a vacuum sheet formation zone G-2, a washing zone G-3, a drying zone G-4, and finally a vacuum release zone G-5 extending between the point of filter cake discharge and the point of resubmergence in the pulp.

The operating zones G-1 and G-2 are functionally separated from each other by a bridge M-1 which comprises a pair of baffle plates 117 and 118 extending from the arcuate bottom portion 110 radially into the annular channel 86 of the drum and substantially conforming to the profile of that channel. These baffle plates are separated from each other a distance sufficient to prevent short circuiting of liquid between the zones G-1 and G-2.

The operating zones G-2 and G-3 are functionally separated by a bridge plate M-2 extending radially from a curved baffle 119 into the recessed annular channel 86. The curved baffle registering with the outer periphery of the filter drum interconnects the sidewalls 102a and 102b of the lower part 102 of the peripheral valve, and at its upper end forms

with the plate M-2 a pocket 120 for a liquid seal. This curved baffle 119 separates a curved inner flow channel 122 from a curved outer flow channel 123, which flow channels provide communication for zones G-2 and G-3 respectively with the barometric discharge leg 88a.

The operating zones G-3 and G-4 are functionally separated from each other by a bridge M-3 comprising a pair of radially directed baffle plates 124 and 125 extending from the bottom 105 of arcuate upper member 103 into the annular channel 86, substantially conforming to the profile of the channel. The baffle plates 124 and 125 are spaced apart a distance sufficient to avoid short circuiting between zones G-3 and G-4.

The next following zone G-5 is the zone of vacuum release where the filter cake is being removed from the filter media, and where the drainage channels 87 of the drum are vented until they reach the point of resubmergence into the pulp.

Zones G-4 and G-5 are functionally subdivided by means of an inwardly inclined tapering chute or scoop Q (see FIGS. 20 and 20a) extending into the annular channel 86 to receive liquid from zone G-4. The wide mouth edge 126 of this scoop functionally represents a line of demarcation between zones G-4 and G-5. This scoop is composed of an upper wide end portion Q-1 fixed to the arcuate upper member 103, and a lower narrow end portion Q-2 fixed to the vat. This scoop is of rectangular cross-sectional shape (see FIG. 20a) conforming to the contour of the annular channel 86 and has sidewalls 126a and 126b. This scoop connects with an arcuate flow channel 127, to provide flow communication between zone G-4 and the gravity discharge leg 88b. Flow channel 127 is formed by an arcuate baffle wall 128 which interconnects sidewalls 102a and 102b and extends from the lower narrow end of the scoop along the outer periphery of the filter drum, thus running substantially parallel to the curvature of the adjacent side of the vat. Baffle wall 128 together with the annular channel 86 also constitutes a curved flow channel 129 parallel to channel 127, providing communication between zone G-1 and the gravity discharge leg 88b.

As the filter drum rotates, the drainage channels 87 passing through the zone G-5 of vacuum release are blocked to a large extent by the sides 126a and 126b of the scoop (see FIG. 20a). Nevertheless, air passing through the filter media of this vented zone will sweep away residual liquid from the drainage channels 87 into the curved flow channel 129.

From the foregoing description of the filtration cycle it will be seen that the sum total of zones G-2 and G-3, covered by an arc A-1, communicate with the barometric discharge leg 88a via flow channels 122 and 123 respectively as indicated by the various flow arrows leading into this barometric leg. The sum total of zones G-4, G-5, and G-1, covered by an arc A-2, communicate with the gravity discharge leg 88b via flow channels 127 and 129 as indicated by the flow arrows leading into this gravity leg.

The drum filter unit of FIG. 24 differs from the one in FIG. 19 above described, in that an annular recessed collecting channel 130 is provided at the end of the drum structure, involving the cascading feature described above and indicated here by arrow T-3. Therefore, the drum structure comprises a cylindrical body portion 131 of diameter D-3 and length E-3 surrounded by filter media 132 covering the drainage channels 133, a reduced short cylindrical end portion 134 of diameter D-4 and length E-4, an end closure plate 136, a transverse annular wall 135 interconnecting the cylindrical portions 131 and 134 are providing the one sidewall of the collecting channel 130, and a transverse annular wall 135a providing the other sidewall of collecting channel 130.

The filter drum rotated by drive means 136a operates in a vat 137 which has a high end wall 138 to support a bearing 139 for trunnion 140 sealingly penetrating the end wall which is high enough to accommodate the pulp level P.L. The opposite low end wall 141 of the vat supports a bearing 142 for trunnion 143 extending freely above the end wall 141 since the end of the filter drum is sealed by one of two deckle strap

devices S-3 and S-4 associated with respective sides of the peripheral valve construction which surrounds the annular collecting channel 130. Each deckle strap device has a deckle strap element 144 the ends of which are anchored at 144a and 144b in FIG. 25. In device S-3 the deckle strap element 144 sealingly cooperates with prepared conical face of an annular band 144c surrounding and fixed to ribs 133a, as well as with the prepared transverse face of the sidewall of the annular valve structure or vacuum box. In device S-4 the deckle strap element sealingly cooperates with the other side of the annular valve structure as well as with the prepared conical face of an end rim 144d provided on the drum structure. The vat (see FIG. 31) has a barometric filtrate discharge leg 145 and a gravity filtrate discharge leg 145a, corresponding to discharge legs 88a and 88b respectively in the embodiment of FIGS. 19, 20, 28, and 29.

The annular valve construction and the filtration cycle of the FIG. 24 embodiment are in substance the same as those represented in FIG. 19 described above.

Greatly enlarged details of the deckle strap device indicated in FIG. 25, are shown in FIGS. 25a, 25b, 25c, 25d. In this embodiment of the deckle strap element there is a core wire 146 the ends of which are anchored at points 144a and 144b respectively (see FIG. 25) upon the side of the annular valve construction in the manner shown in FIG. 25a, one end of the wire being fixed, the other end being adjustable to adjust the tension of the wire.

The core wire is surrounded by tubular sealing member or jacket of resiliently flexible material such as rubber or the like, which extends around the filter drum with a gap K between the ends of this jacket (see FIG. 25) located well within the zone G-5 of vacuum release (see FIG. 20). According to FIG. 25d the tubular sealing means comprise a first or inner tubular element 148 of substantial wall thickness surrounding the core wire, and a second or outer tubular element 149. The inner element provides the backing or cushion for the surrounding element which latter in turn provides the wear surface of the deckle strap element relative to the rotating drum.

The anchoring of the fixed end of this deckle strap element is illustrated in the detail sectional views of FIGS. 25b and 25c which are self-explanatory.

Another form of the anchored deckle strap element is FIG. 25e, and comprises a core wire 150 around which is molded a thick-walled jacket 151 of resiliently flexible wear material. Still another form of the deckle strap element in FIG. 25f comprises a core wire 152, a relatively thick-walled jacket 153 of resiliently flexible material molded around the core wire, and an outer tubular wear element 154 similar to that of FIG. 25d, surrounding the molded material.

FIG. 28 illustrates the invention by presenting the cake discharge side of the filter of FIGS. 19 and 20, with sidewall of the vat partially broken away to expose part of the recessed collecting channel cooperating with the surrounding peripheral valve construction. The aforementioned cake discharge blades 109 are supported and may be adjusted by bolts.

In FIG. 30 which represents the cake discharge side of the filter of FIG. 24, the sidewall of the vat is similarly broken away to illustrate the invention. The cake discharge blade 162 is supported and may be adjusted by bolts.

In summary, it will be seen that this invention provides an improved rotary drum filter in the nature of pulp washers or thickeners preferably suited for handling large volumes of filtrate liquid. This filter comprises a novel fixed peripheral or perimeter valve surrounding the rotating filter drum. This valve construction avoids certain structural and functional problems inherent in earlier valve constructions and of the deckle strap devices associated therewith, and it is superior in regard to operational efficiency. The novel perimeter valve comprises a lower part integral with the vat and connected to a barometric leg, and a complementary upper part or arch-shaped member detachably connected to the vat.

Cooperation between the perimeter valve and the filter drum is such as to allow for hydraulically efficient downward stream-flow of the filtrate liquid directly to the lowest point of the vat, thereby potentially minimizing the required length of the barometric leg as well as filtrate pumping costs in case of countercurrent filter-washing operation. The improved valve construction avoids previous sealing problems in the operation of the valve, by cancelling out the effect of atmospheric pressure acting upon the valve area, and by the provision of an efficient duplex deckle strap arrangement, that is a deckle strap sealing device at each side of the valve structure, as well as by improved constructions of the deckle strap devices themselves.

In addition, this invention allows for great flexibility in design and capacity determinations of this filter unit, inasmuch as the valve structure may be disposed either between the end portions, or at one end of the filter drum.

It will be understood that each of the elements or two or more together, of the apparatus herein described, may also find useful application in rotary drum filters differing from the type described above. Furthermore, while the invention has been illustrated and described as embodied in a continuous rotary drum filter comprising a perimeter valve surrounding the filter drum, it is not intended to be limited to the details shown, since various modifications and structural as well as functional changes may be made without departing from the spirit of the present invention.

I claim:

1. A continuous rotary drum filter which comprises a horizontal rotary drum structure having an annular recess of substantial depth intermediate its ends, which recess has rectangular cross-sectional configuration, with a relatively short cylindrical portion concentric with the drum axis, and of substantially smaller diameter than said end portions, and annular flat sidewall portions of said recess extending transversely of the drum axis and rigidly interconnecting the inner ends of said drum end portions with the respective outer ends of said intermediate cylindrical portion, said drum end portions being formed outwardly with filtrate drainage channels laterally adjoining one another around the periphery of the drum portions, and extending parallel to the drum axis from end to end of the respective drum end portions, said channels being closed at their outer ends and open at their inner ends to communicate with said annular recess, a peripheral annular stationary valve structure surrounding said annular recess and constituting therewith an annular channel providing an annular filtrate collecting zone, a first partition means extending from the bottom portion of the valve structure into said annular recess, and effective to functionally separate an initial gravity filtration zone from an adjoining first vacuum filtration zone and subsequent vacuum cake-washing zone, a gravity filtrate outlet leading from the gravity filtration zone of said valve structure, a vacuum filtrate discharge connection leading from said valve structure for delivering filtrate liquid and spent wash liquor, a second partition means located at the top portion of said drum structure, and functionally separating said vacuum cake-washing zone from an adjoining subsequent cake drying zone, combined blank-off baffle and drainage means located at the descending side of the drum structure, constructed and arranged to provide a cake discharge zone by blocking off the inner ends of the horizontal filtrate drainage channels in that zone, while also providing below said cake discharge zone a drainage duct communicating upwardly with said cake-drying zone, and communicating downwardly with said gravity filtrate outlet, a first deckle strap device provided at one side of said peripheral valve structure for sealing that side against the adjacent portion of the drum structure, a second deckle strap device provided at the opposite side of said annular structure for sealing that side against the adjacent portion of the drum structure, tank structure endwise supporting said drum structure for rotation about a horizontal axis, so that the drum structure is partially submerged in a suspension supplied for filtration, and means fixing said tank structure and said peripheral valve structure relative to one another.

2. The filter according to claim 1, wherein said drum structure has cylindrical end portions of uniform diameter, separated by said annular recess.

3. The filter according to claim 1, wherein said combined blank-off and baffle means comprise a scoop-shaped shell of rectangular cross-sectional configuration conforming to and extending into said annular recess, and having an upwardly open end portion terminating close to the bottom of said annular recess and defining the upper end of the cake discharge zone, said scoop-shaped shell having sidewalls effective to blank off the respective horizontal drainage channels in said cake discharge zone, with a baffle wall extending downwardly from said scoop-shaped shell, and constituting therewith and with said valve structure the drainage duct for said cake-drying zone, while also defining an adjacent inner drainage channel for the gravity filtrate.

4. The filter according to claim 1, wherein the deckle strap of said deckle strap devices comprises a wire core, a tubular jacket of sealing material surrounding said core and bonded thereto, and means for anchoring the ends of said wire core upon said peripheral valve construction, said deckle strap member being disposed so as to have sealing contact with said valve construction and with said filter drum.

5. The filter according to claim 1, with the addition of a third partition means located at the rising side of the drum structure, and functionally separating said first vacuum filtration zone against the adjoining subsequent vacuum cake washing zone, and a curved baffle extending from said third partition means downwardly generally following the curvature of the outer periphery of the drum structure, and defining an inner vacuum drainage channel for vacuum filtrate, and an outer adjacent vacuum drainage channel for spent wash liquid, both drainage channels communicating with said vacuum filtrate connection.

6. The filter according to claim 1, wherein reinforcement in the drum structure is provided, which comprises one set of radial spider arms extending in a plane transversal of the drum axis, adjacent to one side of said annular recessed channel, another set of radial spider arms extending in a plane parallel to said first-mentioned plane and adjacent the other side of said annular recessed channel, and a stub shaft coaxial with the drum axis and rigidly interconnecting said sets of spider arms.

7. The filter according to claim 1, wherein said peripheral valve structure comprises a lower arcuate portion.

8. The filter according to claim 7, wherein said tank structure is shaped substantially to conform to the curvature of said valve structure, and said lower part of the valve structure is integrated into said tank structure.

9. The filter according to claim 1, wherein at least one side of said valve structure has an outer lateral annular face, and the associated deckle strap device comprises a ring member fixed to the drum structure in concentrically spaced relationship therewith, and having a prepared outer conical face tapering down towards said lateral face and terminating adjacent thereto, and a deckle strap element of circular cross section sealingly engaging said conical face on the rotating drum, and thus to be urged laterally into sealing engagement with said lateral face, the ends of said element being anchored upon said side of the annular valve structure.

10. The filter according to claim 9, wherein said deckle strap element is in the form of a tubular member, and tensioning means are provided for tensioning the same around said conical face, said tensioning means comprising a core wire surrounded by said tubular member, and means for anchoring the ends of said core wire upon the adjoining side of said peripheral annular stationary valve structure.

11. The filter according to claim 1, wherein the deckle strap of the deckle strap device is of circular cross-sectional configuration, and disposed to have sealing contact with said valve construction and with said drum structure.

12. The filter according to claim 1, wherein at least one side of said valve structure has an outer lateral face, and the associated deckle strap device comprises a ring member fixed to

the structure in concentrically spaced relationship with said lateral face, and having a prepared outer conical face tapering down towards said lateral face and terminating adjacent thereto, and a deckle strap element of circular cross section sealingly engaging said conical face on the rotating drum, and thus to be urged laterally into sealing engagement with said lateral face.

13. The filter according to claim 1, wherein the deckle strap of said deckle strap device is of circular cross section, and tensioning means are provided internally therein.

14. A continuous rotary drum filter which comprises a horizontal rotary drum structure having a main drum section and an annular recess of substantial depth at one end, said annular recess, having rectangular cross-sectional configuration, being formed by a relatively short cylindrical portion concentric with the drum axis, an inner annular flat wall portion in a plane transversal of the drum axis, and rigidly interconnecting the mutually adjacent ends of said main drum section and said short cylindrical portion, an outer annular flat wall portion concentric with and parallel to said inner annular wall portion, said main drum section being formed outwardly with filtrate drainage channels laterally adjoining one another around the periphery of said main drum section and extending parallel to the drum axis from end to end of said main drum section, and open at one end so as to communicate with said annular recess, and closed at the opposite end, a peripheral annular stationary valve structure surrounding said annular recess and constituting therewith an annular channel providing an annular filtrate-collecting zone, a first partition means connected internally to said valve structure at the bottom portion of the drum structure, conforming to said rectangular cross-sectional configuration, and constructed and arranged so as to functionally separate an initial gravity filtration zone from an adjoining subsequent first vacuum filtration zone and subsequent vacuum cake-washing zone, a gravity filtrate outlet leading from the gravity filtration zone of said valve structure, a vacuum filtrate discharge connection leading from the valve structure for delivering vacuum filtrate liquid and spent wash liquor, a second partition means located at the top portions of said drum structure, and functionally separating said vacuum cake-washing zone from an adjoining subsequent cake-drying zone, combined blank-off baffle and drainage means located at the descending side of the drum structure, constructed and arranged to provide a cake discharge zone by blanking off the inner ends of the horizontal filtrate drainage channels in that zone, while also providing below said cake discharge zone a drainage duct communicating upwardly with said cake-drying zone, and communicating downwardly with said gravity filtrate outlet, a first deckle strap device provided at one side of said peripheral valve structure for sealing that side against the adjacent portion of the drum structure, a second deckle strap device provided at the opposite side of said annular channel structure for sealing that side against said outer annular flat wall portion of the annular recess, a tank structure endwise supporting said drum structure for rotation about a horizontal axis, so that the drum structure is partially submerged in a suspension supplied for filtration, and means fixing said tank structure and said peripheral valve structure relative to one another.

15. The filter according to claim 14, wherein the deckle strap of said deckle strap device comprises a wire core, a tubular jacket of sealing material surrounding said core and bonded thereto, and means for anchoring the ends of said wire core upon said peripheral valve construction, and disposed to have sealing contact with said valve construction and said drum structure.

16. The filter according to claim 14, wherein the deckle strap of said deckle strap device is of circular cross-sectional configuration and disposed to have sealing contact with said valve construction and said drum structure.

17. The filter according to claim 14, wherein at least one side of said valve construction has an outer lateral face, and the associated deckle strap device comprises a ring member

fixed to the drum member in concentrically spaced relationship to said lateral face, and having a prepared outer conical face tapering down towards said lateral face and terminating adjacent thereto, and a deckle strap element of circular cross section sealingly engaging said conical face on the rotating drum, and thus to be urged into sealing engagement with said lateral face.

18. The filter according to claim 14, wherein the deckle strap of said deckle strap device is of circular cross section, and tensioning means are provided internally therein.

19. The filter according to claim 14, with the addition of a third partition means located at the rising side of the drum structure, and functionally separating said first vacuum filtration zone against said adjoining subsequent vacuum cake washing zone, and a curved baffle extending from said third partition means downwardly generally following the curvature of the outer periphery of the drum structure and defining an inner vacuum drainage channel for vacuum filtrate, and an outer adjacent vacuum drainage channel for spent wash liquid, both drainage channels communicating with said vacuum filtrate connection.

20. A continuous rotary drum filter operating in a tank provided with a supply of pulp to be filtered, and which comprises a horizontal rotary drum structure presenting a peripheral drainage deck area, longitudinal liquid drainage channels formed on said drainage deck area, laterally adjoining one another around the periphery of said deck area coextensive with the drum axis, and adapted for delivery of liquid from said drainage channels to a peripheral collecting zone, filter media surrounding and closing said drainage channels from end to end thereof, and further having a stationary annular valve structure surrounding said annular liquid-collecting zone, and having internal partitions defining the filtration cycle, and bottom outlet means for filtrate liquid from a vacuum filtration zone, and having deckle strap devices surrounding the drum and providing sealing relationship between the annular stationary valve structure and the rotating drum, said drum structure being endwise supported by a tank structure for rotation about a horizontal axis, whereby the drum structure is partially submerged in pulp for filtration, and the tank is fixed relative to the valve structure,

characterized thereby that said drum structure is formed with an annular recess of substantial depth surrounded by said annular valve structure, with baffle means extending internally from said annular structure into said annular recess in form-fitting relationship therewith, said baffle means being constructed and arranged so as to define a filtration cycle having:

- a. a vacuum filtration zone submerged in pulp to be filtered to form filter cake on said filter media while filtrate liquid passes from the bottom portion of said annular valve structure;
- b. a vacuum cake-washing or dewatering zone effective after emergence of the filter cake from the pulp to allow liquid to flow from the respective longitudinal drainage channels of that zone into said annular recess or collecting channel and in said channel down at the ascending side thereof along a shortened path spaced radially inwardly from said longitudinal drainage channels for delivery from said annular valve structure;
- c. a cake-drying zone following said dewatering zone, at the descending side of the drum, to allow liquid to flow from the respective horizontal drainage channels of that zone into said annular collecting channel and in said channel down at the descending side thereof along a shortened path spaced radially inwardly from said horizontal drainage channels, the liquid from said drying zone and the liquid from the preceding dewatering zone thus flowing from the top portion of the drum in opposite directions towards delivery from said annular valve structure; and
- d. a vacuum release zone allowing for cake discharge following said cake-drying zone at the descending side of the drum.

21. The drum filter according to claim 20, wherein said annular recess is spaced from both ends of the drum structure, so that said annular recess receives filtrate liquid from both directions.

22. The drum filter according to claim 20, wherein said annular recess is located at one end of the drum structure.

23. The drum filter according to claim 20, wherein said deckle strap devices comprise a deckle strap of circular cross-sectional configuration.

24. The filter drum according to claim 20, wherein one side of said valve structure has an outer lateral face, and the associated deckle strap device comprises a ring member fixed to the drum in concentrically spaced relationship with said lateral face, and having a prepared outer conical face tapering down towards said lateral face and terminating adjacent thereto, and a deckle strap of circular cross-sectional configuration sealingly engaging said conical face on the rotating drum structure, and thus being urged into sealing engagement with said lateral face.

25. The drum filter according to claim 21, wherein said drum structure has cylindrical end portions of uniform diameter, separated by said annular recess.

26. The drum filter according to claim 20, wherein said recess is of rectangular configuration.

27. The drum filter according to claim 20, wherein said tank structure is of half-round cross-sectional configuration, said annular valve structure comprises a lower half integrated into said half-round configuration of the tank structure, and an upper half detachably connected to the lower half.

28. The drum filter according to claim 20, wherein said baffle means are constructed and arranged so that said filtration cycle comprises an atmospheric pressure zone for cake discharge following said cake-drying zone, and extending downwardly sufficiently far into the pulp to provide a gravity filtration zone in the pulp, preceding said vacuum filtration zone, and outlet means are provided for gravity filtration liquid passing from the bottom portion of said annular valve structure.

29. The drum filter according to claim 28 wherein duct 40

means are provided internally of said annular valve structure for delivering the liquid from said cake-drying zone for discharge at the bottom of said valve structure.

30. The drum filter according to claim 1, wherein the liquid from said vacuum filtration zone and the liquid from said cake-washing or dewatering zone are delivered jointly from the bottom portion of said annular valve structure.

31. A continuous rotary drum filter operating in a tank provided with means for feeding pulp to the tank, and which comprises a horizontal rotary drum structure presenting a peripheral drainage deck area, longitudinal liquid drainage channels formed on said deck area adjoining one another around the periphery of said deck area coextensive with the drum axis, and adapted for delivery of liquid from said 10 drainage channels to a peripheral collecting zone, filter media surrounding and closing said drainage channels from end to end thereof, and further having a stationary annular valve structure surrounding said annular liquid-collecting zone, and having internal partitions defining the filtration cycle, and bottom 15 outlet means for filtrate liquid from a filtration zone, and having deckle strap devices surrounding the drum and providing sealing relationship between the stationary annular valve structure and the rotating drum, said drum structure being endwise supported by a tank structure for rotation about a 20 horizontal axis, whereby the drum structure is partially submerged in pulp for filtration, and the tank is fixed relative to the tank structure, characterized thereby that said drum structure is formed with an annular recess of substantial depth surrounded by said annular valve structure, and sealed relative to 25 said annular valve structure by said deckle strap means, with baffle means extending internally from said annular valve structure into said annular recess in formfitting relationship therewith, said baffle means being constructed and arranged so as to define a filtration cycle having a vacuum filtration 30 zone submerged in pulp to be filtered to form filter cake on said filter media while filtrate liquid passes from the bottom portion of said annular valve structure and a cake discharge zone at the descending side of the drum where the vacuum is broken.
